UNITED STATES PATENT OFFICE

NIKOLAUS HÄRIG, OF PIRMASENS, PALATINATE, GERMANY, ASSIGNOR TO UNITED SHOE MACHINERY CORPORATION, OF PATERSON, NEW JERSEY, A CORPORATION OF NEW JERSEY

METHOD OF MAKING SHOES AND HEELS

Application filed March 23, 1928, Serial No. 264,153, and in Germany April 13, 1927.

This invention relates to improvements in methods of making shoes and to improvements in shoes and heels as articles of manufacture. The invention is herein illustrated in its application to one-piece Louis heels and shoes provided with such heels and to methods of making such heels and shoes, although in certain aspects the invention is not necessarily restricted to heels or shoes of the particular types indicated.

It is customary to cover the rear and sides of a Louis heel before the heel is attached to a shoe and, after attachment of the heel, to cover the breast of the heel by a flap integral with the sole of the shoe. In accordance with this practice the breast covering flap is preliminarily formed by splitting it from the sole and after the sole and heel have been attached to the shoe the sole flap is adhesively secured in place on the heel breast, trimmed flush with the lateral edges of the breast, and then held against the heel under pressure for a substantial length of time to insure proper setting of the adhesive. The covering of the breast of a heel in this manner requires skilled labor and the expenditure of considerable time. Consequently, it is a relatively expensive operation.

One object of the present invention is to avoid the expense and loss of time incident to the covering of breasts of heels in accordance with the method just referred to and yet to insure that the effect obtained in the finished shoe will be as good as or better than would be the case if the more expensive operation above described had been practised.

With this object in view the invention, in one aspect, resides in an improved method of making shoes in accordance with which, as herein exemplified, the desired effect in the finished shoe is obtained without the use of a breast covering split from the sole of the shoe, by coating the bottom surface of the sole and the uncovered breast face of the heel to obliterate the joint between the heel breast and the sole and to simulate the surface appearance of a heel breast covering integral with the sole, and by finishing a narrow strip at the side of the heel, adjacent to the breast corner to simulate the edge appearance of a

heel breast covering integral with the sole of the shoe.

The invention further consists in improvements in shoes produced by the practice of the above-described method and in improvements in Louis heels adapted for use in carrying out that method.

The invention will be explained with reference to the accompanying drawings, in which

Fig. 1 is a view in side elevation of a shoe embodying the present invention, the shoe being shown as it appears before certain finishing operations have been performed upon the sole and heel;

Fig. 2 is a perspective view of the heel shown in Fig. 1;

Fig. 3 is a side elevational view of the heel as it appears before the side covering is applied;

Fig. 4 is a cross-sectional view taken along the line IV—IV of Fig. 3;

Fig. 5 is a perspective view of a shoe like that shown in Figs. 1 and 2, but showing the shoe and heel as they appear after all finishing operations have been performed thereon;

Fig. 6 is an enlarged cross-sectional view of the heel taken along the line VI—VI of Fig. 1;

Fig. 7 is a view in central longitudinal section of the rear of the shoe shown in Fig. 5;

Fig. 8 is a detail cross-sectional view of the shoe taken substantially along the line VIII—VIII of Fig. 7;

Fig. 9 is a perspective view of a heel illustrating an alternative method of fitting the seat face of the heel; and

Fig. 10 is a perspective view of a shoe having its seat face fitted to receive a heel such as that shown in Fig. 9.

In the drawings the invention has been illustrated in connection with one-piece heels as distinguished from heels which are built up from a plurality of lifts or layers.

As illustrated in Figs. 3 and 4, a Louis heel 14 is provided with grooves 16 in its side faces for the reception of the front margins of a covering 18 for the rear and sides of the heel. The grooves 16 extend from the top to the

bottom of the heel and are parallel to the lateral edges of the heel breast. The grooves 16 are located near but somewhat at the rear of the edges or corners of the breast so that when the sides of the heel are covered as by the covering 18 and the front margins of the covering 18 tucked into the grooves, the narrow edge portions of the surface of the heel which are left exposed at the sides of the heel in front of the grooves will be of a width substantially equal to the thickness of the edges at the shank portion of the outsole of a shoe to which the heel is to be attached. These narrow uncovered portions of the heel in front of the grooves 16 are finished to simulate the edges of a breast covering flap split from the sole of the shoe and laid upon the breast face of the heel as will hereinafter be more fully explained. As illustrated in Fig. 8, the edges of the outsole are rounded along the shank and, in order to enhance the effect that a sole flap covers the breast of the heel, the narrow uncovered portions or ribs formed between the grooves 16 and the breast corners, are similarly rounded or beaded as shown at 20, Figs. 3, 4 and 6, to correspond with the rounded cross-sectional contour of the edges of the shank portion of the sole.

The seat face end of the heel has a cupped formation adapting it to fit a heel seat surface formed in the well-known manner upon the bottom of the shoe. The forwardly extending portion of the heel at the upper end of the breast is shown at 22 in Figs. 2 and 7 as being finished to a feather edge so that no noticeable ridge will be formed where it joins the sole and the heightwise curvature of the heel breast is made such that it will merge gradually into and blend with the longitudinal curve or arch of the shank portion of the sole as shown at 34 in Fig. 5. The grooves being parallel to the breast edges, the ribs or beads 20 will continue the lines or curves of the sole edges. At the opposite sides of the heel shown in Figs. 1 to 8, where the upper ends of the uncovered beaded portions 20 terminate, the heel is so shaped that the upper ends of these beaded portions will closely embrace the opposite edges of the outsole S in the manner clearly shown at 24 in Fig. 8, the sole being preferably pared away or beveled during the heel seat fitting operation at these points to adapt it to fit snugly within the rim of the heel so that a close joint is provided between the rim of the heel and the lasted-in portions of the shoe upper. In addition, the upper ends of the beaded portions 20 of the heel which embrace the edges of the sole are illustrated in Fig. 2 as being made very thin so that they will blend readily with the rounded edges of the sole.

After the heel has been attached to the shoe the breast face of the heel and the beaded edge faces 20 are smoothed or buffed at their upper end portions until they are flush

with the corresponding surfaces of the sole along the lines where they join the latter, these lines being indicated at 26 in Fig. 1. Thereafter the uncovered ribs or beaded portions 20 of the heel and the breast surface of the heel are preferably finished to match the finish of the edges and the tread surface, respectively, of the sole. In finishing the beaded portions of the heel the latter may be first stained or otherwise colored to match the color of the edge of the sole after which they may be waxed or otherwise treated, as for example with the edge finishing tool which is used also upon the sole edge, so that the color and surface characteristics of the sole edge are reproduced in the beaded portions of the heel. In order that the breast surface of the heel and the tread surface of the sole shall correspond in color a pigment finish may be applied both to the sole and to the heel breast. The above-described manner of finishing the beaded portions and the breast surface of the heel results in completely obliterating the lines 26 at the joint between the breast of the heel and the sole and as a result the sole edge at each side of the shoe appears to be continuous with the corresponding beaded portion of the heel, while the breast of the heel and the bottom of the shank of the sole also appear to be continuous, as shown in Fig. 5, and the heel has the appearance of having its breast covered by an extension of the sole. If desired, various ornamental and pleasing results may be obtained by applying to the heel breast or to the beaded portions 20, or to both these parts a color finish either contrasting with the color of the sole bottom and sole edge or harmonizing with said color.

While the forwardly extending upper end portion of the heel breast may be reduced to a feather edge, as hereinbefore described, it may sometimes be desirable to provide a shoulder 31 of substantial thickness at the edge of this portion of the heel for engagement with a corresponding shoulder 32 in the outsole of the shoe, as indicated in Fig. 11. In applying to a shoe a heel such as that shown in Fig. 10 the shoulder 31 on the heel is butted against the shoulder 32 on the sole and the breast surface of the heel and bottom surface of the sole are buffed until these two surfaces are flush. It will be noticed that with a construction such as just described it will be unnecessary to do any special fitting at the upper ends of each of the breast corners to facilitate the blending of the beaded breast edge portions of the heel with the edges of the sole.

Having described the invention, what I claim as new and desire to secure by Letters Patent of the United States is:

1. That improvement in the art of making shoes which consists in providing a Louis heel with a thin feather edge extending en-

tirely across the heel at the front end of its seat face and with a breast surface having a heightwise curvature shaped to merge into the lengthwise curvature of the shank portion of the sole of a shoe, attaching the heel to a shoe so as to form a close joint between the upper portion of the heel breast and the sole of the shoe, applying a coating to both the bottom of the sole and the breast of the heel to obliterate said joint and simulate the appearance of the surface of a sole flap covering the heel breast, and finishing a narrow strip at each side of the heel adjacent to the respective breast corner to simulate the appearance of the edge of said sole flap.

2. That improvement in the art of making shoes which consists in fitting a Louis heel to a shoe so as to form a close joint between the upper portion of the heel breast and the bottom surface of the tread sole of the shoe, applying a coating to the bottom surface of the sole and to the uncovered breast face of the heel to obliterate said joint and to simulate the surface appearance of a heel breast covering integral with the sole of the shoe, and finishing a narrow strip at the side of the heel adjacent to the breast corner to simulate the edge appearance of a heel breast covering integral with the sole of the shoe.

3. That improvement in the art of making shoes which consists in forming a bead along the breast edge of each side of a Louis heel and a groove in each side of the heel adjacent to the bead at that side of the heel, applying a cover to the rear and sides of the heel and tucking the opposite lateral edge portions of the cover into said grooves but leaving said beads and the breast face of the heel uncovered, fitting the heel to a shoe so as to form a close joint between the upper portion of the heel breast and the bottom surface of the tread sole of the shoe, applying a coating to the bottom surface of the sole and to the uncovered breast face of the heel to obliterate said joint and to simulate the surface appearance of a heel breast covering integral with the tread sole, and finishing said uncovered beads to match the edge finish of the tread sole to simulate the edge appearance of a heel breast covering integral with the tread sole.

4. In a shoe, the combination with the tread sole, of a Louis heel having an uncovered breast surface merging with the bottom surface of said sole, and uncovered beads severally extending along the opposite lateral edges of the heel breast and merging with the respective lateral edges of the sole to simulate the edge appearance of a heel breast covering integral with the tread sole, the sides of the heel being covered rearwardly of the breast edge beads, and said merging portions of the sole and heel having a coating thereon obliterating the joints between them and imparting a like surface finish to

all said portions so that said sole and heel portions will appear to be continuous.

5. A Louis heel having an uncovered breast surface, an uncovered bead extending along each lateral edge of the heel breast, and a groove in each side of the heel adjacent to the bead on that side of the heel, the breast surface and the beads being shaped and arranged to merge with the bottom surface and lateral edges, respectively, of the tread sole of a shoe to which the heel is to be attached and being coated to match the finish of said portions of the sole to simulate the appearance of a heel breast covering integral with the sole when the heel is attached to the shoe, the heel having a cover upon its rear and side surfaces the forward edges of which are tucked into said grooves.

In testimony whereof I have signed my name to this specification.
